G. W. CAMPBELL.
MORTISING MACHINE.
APPLICATION FILED DEC. 30, 1920.

1,415,790.

Patented May 9, 1922.

UNITED STATES PATENT OFFICE.

GEORGE W. CAMPBELL, OF COLUMBUS, OHIO.

MORTISING MACHINE.

1,415,790.

Specification of Letters Patent.

Patented May 9, 1922.

Application filed December 30, 1920. Serial No. 434,022.

To all whom it may concern:

Be it known that I, GEORGE W. CAMPBELL, a citizen of the United States, residing at Columbus, in the county of Franklin and 5 State of Ohio, have invented a certain new and useful Improvement in Mortising Machines, of which the following is a specification.

The present invention relates to the kind 10 of machine shown and described in the patent issued to me December 31, 1918, No. 1,289,114, and has for its object to simplify and cheapen the construction of such machine and promote the ease and efficiency of 15 its operation.

The invention is embodied in the example herein particularly shown and described, the features of novelty being finally claimed.

In the accompanying drawing—
20 Figure 1 is a side elevation of the machine according to my present improvements.

Fig. 2 is a sectional detail view on a large scale of means actuating and latching the clutch shifting lever.

25 Fig. 3 is a sectional detail of the tool and tool carrier feeding element.

Fig. 4 is a partial detail in side view of the shiftable bar.

30 Fig. 5 is a view looking at the right hand side of what is shown in Fig. 4 with the means for compressing the springs of the clutch shifting lever added.

The present machine as in my former patent referred to includes guide rods 1 and 2 35 connected together at one end by a handle portion 3 and at the other end by a slotted cross bar 4 the upper and lower ends of which are provided with suitable clamps 5 for attaching the machine to the door or 40 other object to be mortised. The carriage for the operating parts is slidably mounted upon the guide rods 1 and 2 and consists of side pieces 6 and 7, a rear connecting piece 11, forward connecting piece 9 and intermediate cross piece 8, the carriage being provided with laterally extending bosses 12 that 45 are sleeved upon the guide rods 1 and 2.

Journalized in the cross piece 11 is a shaft 14 to which is connected the main operating 50 wheel 15, and pivoted upon said shaft 14 is an oscillating arm 17 carrying the tool holder 18. The tool shaft 19 is pinned at 18^a in the holder 18 so as to be capable of rotation therein. The tool 19^a is removably screwed 55 into the forward end of the tool shaft. The forward end of the oscillating arm 17 is

made with a housing 17^a within which is located a pinion 20 pinned to the tool shaft. The pinion 20 is in mesh with the teeth 21 on the side of the operating wheel 15 so that 60 when the wheel 15 is operated the tool will be revolved.

Revolutely mounted in bearings 22 which extend laterally from the carrier frame is a screw 23 upon which is threaded a nut or 65 head 24. The head 24 is swivelly connected with a block 25 that is slidably mounted in ways 27 integrally formed with the tool holder 17. Loosely mounted upon an unthreaded portion of the screw 23 are beveled 70 gears 28 and 29 and splined to said unthreaded portion of the screw between these gears is a clutch member 30 arranged to be shifted along the spline so as to be thrown into engagement with either one of the gears 75 as in my former patent referred to. A beveled pinion 35 is in mesh with both the gears 28 and 29 and has its shaft journaled in the frame of the carrier, the opposite end of the shaft being provided with a pinion 80 36 (shown in dotted lines in Fig. 1) in mesh with the internal gear teeth 37 on the main operating wheel so that as said wheel is operated the gears 28 and 29 will be operated 85 in opposite directions. Pivotedly connected to the carrier frame at 40 is a shifting yoke-like lever 39, one arm 41 of which engages the grooved clutch collar 30. Said yoke-like lever carries a rod upon which slides a spool 47 and interposed between said spool and the 90 ends of the yoke-like lever are coil springs 48 and 49 either of which is adapted to be placed under compression when the spool is shifted against it. The yoke-like lever 39 is initially tilted so as to shift the clutch 30 95 upon the compression of one of the springs 48 and 49 because of the movement of the spool 47 which is connected with and actuated by a fork 50 on a beveled projection 51^b on the shiftable bar 57. Means for preventing the oscillation of the lever 39 until the proper spring is fully compressed consists of two pivoted latches 52 and 53 each of which is provided with a shoulder 54 and a beveled portion 55. When the lever is 105 shifted to one position the shoulder on one of the latches will engage the projection 56 and retain the lever in its shifted position. The lever 39 will ordinarily be held in this position until the shifting device 57 is near the 110 extreme limit of its movement, but will be finally released by the beveled projection 51^b

coming in contact with the inclined portion of the latch which forces the latch out of engagement with the projection on the lever after the corresponding spring has been placed under compression by the movement of the bar 57. The spring then quickly shifts the lever so as to throw the clutch 30 from one gear to the other, the latch being at the same time returned to normal latching 10 position by a spring 63. The shifting of the bar 57 to accomplish this begins to take place near the end of each oscillatory movement of the tool holder as in my former patent. But in the present instance the side of 15 the yoke-like lever is provided with a beveled projection 39^a extending at right angles to the plane of its oscillation and upon the frame is a socket member 7^a having a spring held plunger pin 80 beveled at its end to coact with the beveled projection 39^a. 20 When a spring 48 or 49 is compressed the plunger pin 80 rides up one side of the pin 39^a and after the apices pass the opposite side acts to throw the yoke to full clutching 25 position and holds the clutch securely engaged until the yoke lever is similarly actuated in the opposite direction. The 30 rotatable mounted thereon a screw 58 one half of which is provided with right hand threads and the other with left-hand threads. Threaded on each half of this screw are sleeves 59 and 60 each of which has a pin as shown at 61 that projects through a slot extending lengthwise of the bar 57. The screw 35 58 has finger piece 62 by which it may be turned so as to simultaneously and uniformly adjust the pins 61 to or from the center of the machine, said pins being held 40 from turning with the screw as in my former patent referred to. When the tool holder strikes one of the pins 61 and moves the bar 57 the fork 50 will move the spool 47 placing one of the springs 48 or 49 under compression 45 and then by reason of the beveled projection 51^b on said bar finally release the latch which is holding the lever 39 and thereby permit the shifting of this lever by the spring which has been placed under compression. 50

As is usual in machines of this character, means are provided for feeding the tool into the mortise at the end of each oscillatory movement of the tool carrier. In the 55 present machine this is accomplished as follows. The guide rail 1 is formed with worm teeth 65 engaged by a worm 66 mounted on an eccentric sleeve 67 having a finger piece 67^a, said worm having at its lower end a ratchet 69. Secured to the shiftable bar 57 on each side of this ratchet wheel are reversely acting spring pawls 70 which alternately engage the ratchet wheel at the 60 end of each oscillatory movement of the tool carrier and thereby turn the worm 65 through a portion of a revolution so that each time the worm is actuated the tool is moved toward the work. A toothless space 65^a is left at the forward end of the worm rack to nullify the operation of the worm 70 and therefore limit the feed of the tool carrier. When it is desired to return the carrier to a proper position to cut a fresh mortise the worm is drawn out of engagement with the rack by turning the eccentric 75 sleeve with the finger piece 67^a against the holding spring 68 so that the worm can pass freely over the worm rack, after which the carrier may be readily slid along the guides 1 and 2. The spring 68 is designed 80 to hold the worm yieldingly either in or out of engagement with the rack.

The central portion of the cross bar 8 which in the present instance is placed forward of the bearing 14 is formed with a 85 curved groove 8^a and the rear end of the tool holder is provided with a pin 8^b to enter said groove. This construction allows the tool holder and tool a longitudinal movement relative the other parts, this movement being determined by the curvature of the groove 8^a of the bar 8 as the pin 8^b travels therein during the oscillatory movement, the curvature of this groove being such as to cause the cutting end of the 90 tool to travel in a substantially straight line throughout the entire length of the mortise. By the present construction both frames are greatly shortened and the necessity for providing ball or roller bearings 100 to prevent binding where the shaft crosses the main axis of oscillation is avoided.

From the foregoing it will be observed that, except as to the operation of those details by which the present construction is 105 distinguished from the construction of my former patent the operation generally is the same. That is to say by turning the large main operating wheel in one direction the tool or bit is turned and at the same time automatically swung back and forth to 110 cut an elongated mortise to the depth desired and permitted by the machine.

The forms of the parts can be changed without departing from the gist of the invention claimed. 115

What I claim is:

1. In a mortising machine, a main frame, an oscillatory tool carried by said frame, a screw having an operative connection with 120 said tool, means for rotating said screw in opposite directions comprising a shiftable clutch, a pivoted shifting lever for said clutch, a pair of springs carried by said lever, a latch for said lever in each of its 125 positions, a shiftable bar operated by the oscillations of the tool adapted to compress one or the other of said springs for initially shifting said lever, a beveled member on said shifting lever extending from the side 130

thereof at right angles to the plane of its oscillation, and a beveled spring-actuated pin on the main frame of the machine co-operating with said beveled member on the 5 shifting lever to finally shift said clutch into operative position.

2. In a mortising machine, the combination with a main frame, and a sliding frame carrying an oscillated tool, of means for 10 feeding the sliding frame comprising a rack member formed on said frame, a worm on the sliding frame engaging said rack, a bar sliding with the oscillations of the tool, and means actuated by the sliding bar for intermittently rotating said worm.

3. In a mortising machine, an oscillating

support, a tool pivotally connected to said support to oscillate therewith and thereon, the connection being such as to permit an axial movement of said tool relative thereto, 20 mechanism for oscillating said tool, the connection between the tool and mechanism being such as to permit pivotal and axial movement of said tool relative thereto, a curved guide in advance of the center of 25 oscillation of the tool support and means associated with the tool for engaging said guide, said guide and engaging means adapted to cause the operative end of the tool to oscillate in substantially a straight 30 line.

GEORGE W. CAMPBELL.
